ATTORNEY.

UNITED STATES PATENT OFFICE.

HOMER E. EYMAN, OF LANCASTER, OHIO.

DESIGN FOR A SCARF-RACK.

SPECIFICATION forming part of Design No. 25,059, dated January 21, 1896.

Application filed November 30, 1895. Serial No. 570,706. Term of patent 7 years.

To all whom it may concern:

Be it known that I, HOMER E. EYMAN, of Lancaster, in the county of Fairfield and State of Ohio, have invented and produced a new and original Design for a Scarf-Rack, of which the following is a full, clear, and exact description.

Reference is to be had to the accompanying drawing, forming a part of this specification, which represents a perspective view of a scarf-rack embodying my new design.

The leading feature of my design consists of a scarf-rack having the spaced and convergent ornamental holders rising from a base and presenting convergent openings.

A more specific description of the design in its entirety is as follows: A base *a* is segmental in general contour. Its front curved edge

is rabbeted, and in the angle of the rabbet a round board appears, while the converging ²⁰ side edges *b* are plain and are concaved. At the rear narrowed end of the base appears an ornamental handle *c* in the form of a scroll. The holders *d* *e* are convergent, the inner members *d* joining at the top and the exterior ²⁵ convergent members *e* being spaced at their upper ends and rising parallel above the inner members *d*, the whole presenting an inverted-Y shape.

I claim—

The design for a scarf rack herein shown and described.

HOMER E. EYMAN.
